G. B. LOWDEN

CHILD'S AIRPLANE VEHICLE

Filed Aug. 27, 1923

UNITED STATES PATENT OFFICE.

GEORGE B. LOWDEN, OF SAN FRANCISCO, CALIFORNIA.

CHILD'S AIRPLANE VEHICLE.

Application filed August 27, 1923. Serial No. 659,558.

To all whom it may concern:

Be it known that I, GEORGE B. LOWDEN, a subject of the King of Yugoslavia, residing at San Francisco, in the county of San Francisco and State of California, have invented new and useful Improvements in Children's Airplane Vehicles, of which the following is a specification.

This invention relates to improvements in children's vehicles of the type which are propelled by pushing with the feet against the ground.

An object of the invention is to provide a child's vehicle of the character described which simulates an airplane, is simply constructed, inexpensive, compact, strong and durable, which will have considerable stability and is capable of being easily steered.

Another object of the invention is to provide a child's vehicle of the character described which is of novel construction and arrangement, the special parts and elements being easy to construct and assemble and providing maximum strength and stability and at the same time causing the vehicle to closely simulate an airplane.

With the above mentioned and other objects in view, the invention consists in the novel construction and combination of parts hereinafter described, illustrated in the accompanying drawing, and set forth in the claims hereto appended, it being understood that various changes in the form, proportion, size and minor details of construction within the scope of the claims may be resorted to without departing from the spirit or sacrificing any of the advantages of the invention.

Referring to the drawing:

Fig. 1 represents a side elevation of a vehicle constructed in accordance with the invention.

Fig. 2 represents a top plan view of the vehicle.

Fig. 3 is a sectional view taken on lines 3-3 of Fig. 1.

In the embodiment of the invention shown in the accompanying drawing, the vehicle is made up of a body portion 1, which simulates the fuselage of an airplane and a steering portion 2 which simulates the wings and forward part of the fuselage of an airplane. The body portion 1 is made up of upper and lower pairs of spaced bars 3 and 4. These bars are joined by posts

5, 6, 7 and 8, which posts extend between the pairs of bars and between the bars of each pair, and are secured in place by fastening elements 9 driven through the bars 60 into the posts. The post 7 which is disposed intermediate of the ends of the body portion but nearer to the rear end, extends below the plane of the lower pair of bars 4 and has a wheel 10 mounted thereon, which wheel is preferably in the form of a circular disk. At the rear end of the upper pair of bars there is mounted a structure 11 which simulates the horizontal and vertical rudders of an airplane and which also 65 may serve as a seat. Mounted on the upper end of the post 7 and extending over the upper edges of the bars 3 is a seat 12. A similar seat 13 is mounted on the upper end of the post 6 and rests on the upper edges 70 of the bars 3. These seats are spaced from one another and located between the ends of the body portions 1 in a position which will provide for an effective balance in order that two or more children may ride 75 on the vehicle at the same time. This structure, while narrow and consisting of but few parts, is compact, strong and durable.

The steering portion of the vehicle 2 comprises essentially an upright body plate 14 85 which in this instance, is of substantially hour glass shape and made of wood. The entire device is preferably made of wood, although other material may be used. This upright body plate 14 at its lower end carries a horizontal axle 15 projecting from opposite sides thereof, on which axle wheels 16 are mounted. The plate is sufficiently wide at its lower end to provide for disposing of the wheels far enough apart and 90 with respect to the wheel 10, to provide adequate stability. The plate is provided with a vertical slot 17 extending from the upper edge downwardly to a point near its lower edge. In this slot is mounted a post 18 of rectilinear cross section and which post 95 is of less width than the width of the slot. Extending between the posts and the sides of the slot are upper and lower pairs of bars 19 and 20. The bars of each pair are disposed in spaced parallel relation to the upper and lower extremities of the slot, the lower bars resting on the bottom of the slot and the upper bars terminating flush with the upper edge of the slot. Spacing strips 110 21 are mounted on opposite sides of the post 18 and fill the space between opposite

sides of said post and the opposed walls of the slot, the ends of said strips abutting the edges of the bars 19 and 20. Fastening elements 22 are driven, preferably through 5 the narrow portion of the plate 14, and through the strips 21 and into the post 18 so as to hold these parts assembled.

The pairs of bars 19 and 20 engage in the plate 14 at points intermediate of the 10 ends of the bars but nearer to the rear ends thereof and at the rear ends of said bars there are provided bearing blocks 23 which are mounted between the bars of each pair and are adapted to be engaged by the ends 15 of the post 5 of the body portion 1. Pivots 24 are inserted through the blocks 23 and into the ends of the post 5 so as to provide an axis for turning the steering portion 2 relative to the body portion 1.

20 Attached to the bars 19 and 20 are upper and lower wing structures 25 and 26, each of which comprises three spaced parallel bars 27 secured centrally of their ends by fastening elements 28, to the bars 19 and 20 25 and extending laterally on opposite sides of said bars 19 and 20. Cross pieces 29 are secured to the outer ends of said bars 27 and the wing structures are thus provided in the nature of substantially rectangular 30 skeleton frames. The strips 29 are placed, one across each end of the upper and lower planes on the under sides thereof and the bars 27 forming the planes are secured to said strips by suitable fastening elements as 35 shown in Fig. 2. The wings may be readily grasped in the steering and handling of the vehicle, the bars 27 providing effective grips. The center of the three bars 27 of the upper 40 wing structure extends along and engages the upper edge of the plate 14. The corresponding bar of the lower wing structure is provided with a recess 30 in which the plate 14 engages. Due to these arrangements of the bars the wing structure is made strong 45 and durable and given considerable stability so that pressure on either side will not be likely to cause the vehicle to up-set or tilt.

At the front ends of the bars 19 and 20 50 there is provided a post 31 secured to and joining said bars, and attached to the post is a propeller 32 arranged so that it will be turned when the vehicle is moved forwardly. One of the important features of the invention is the construction and arrangement of 55 the plate 14 and other associated parts.

Through employment of this arrangement, the device may be made entirely of wood and of but few parts and at the same time provide maximum strength, lightness as to weight, and stability. Children sitting on 60 the seats 12 and 13, may use the bars of the lower wing structure as foot rests and the bars of the upper wing structure as grips in steering the vehicle. The open work wing construction facilitates the handling of the 65 vehicle as a whole.

I claim:

1. A child's airplane vehicle comprising an elongated body portion of skeleton construction, a wheel carried by the body portion intermediate of the ends thereof, a seat on the body portion, an upright body plate, wheels carried on opposite sides and at the lower end of the body plate, said body plate having a slot extending from its upper end 70 downwardly therein between the sides thereof, bars extending through the slot in the plate adjacent the upper and lower extremities of the slot, one end of said body portion being disposed between the inner 75 ends of said bars, means for pivotally connecting said end of the body portion with said bars, a post mounted in the slot and engaging said bars and transverse frames simulating wings mounted on the upper and 80 lower bars and extending laterally on opposite sides thereof.

2. A child's airplane vehicle comprising an elongated body portion of skeleton construction, a wheel carried by the body portion 90 intermediate of the ends thereof, a seat on the body portion, an upright body plate, wheels carried on opposite sides and at the lower end of the body plate, said body plate having a slot extending from its upper end 95 downwardly therein between the sides thereof, bars extending through the slot in the plate adjacent the upper and lower extremities of the slot, one end of said body portion being disposed between the inner 100 ends of said bars, means for pivotally connecting said end of the body portion with said bars, a post mounted on the upper and lower bars and frames simulating wings extending laterally on opposite sides thereof, 105 said plate engaging said frames and being disposed substantially centrally of the frames.

GEORGE B. LOWDEN.
